UNITED STATES PATENT OFFICE.

JOHN YOUNG, OF FARMINGTON, NEW HAMPSHIRE.

PIPE-CO尤PLING.

SPECIFICATION forming part of Letters Patent No. 792,377, dated June 13, 1905.

Application filed February 8, 1904. Serial No. 191,901.

To all whom it may concern:

Be it known that I, JOHN YOUNG, a citizen of the United States, residing at Farmington, in the county of Strafford and State of New Hampshire, have invented certain new and useful Improvements in Detachable Pipe-Couplings, of which the following is a specification.

My invention relates to improvements in joining adjacent ends of pipes firmly and tightly without skilled labor or the use of solder, screw-threads, &c. I attain these objects by the mechanism illustrated in the accompanying drawings, in which—

15 Figure 1 is a longitudinal section of the pipe-coupling according to my invention. Figs. 2 and 3 are detailed views of collars on an enlarged scale; and Figs. 4 and 5 are modifications of collars shown in Figs. 2 and 3, respectively.

This coupling is composed of a union A, collars B and C and modifications, and clamping-rings D D.

E E are ends of pipes to be connected.

25 The union A is a short piece of simple pipe with screw-threads cut on the outside of each end, and the center of outside may be octagonal for the wrench.

B is a spiral wedge-shaped collar consisting 30 of a piece of metal with width of both ends gradually converging to a point, wound in spiral form one and seven-eighths times its circumference. In B' the piece of metal is narrower and wound from two and one-half 35 to three and one-half times its circumference.

C is a wedge-shaped collar formed of a spirally-wound piece of metal. The end b of the collar is of suitable thickness to bear against the union A, and from the end b the spiral 40 collar gradually decreases in thickness to the lower end, so as to produce the wedge shape desired.

In the form of collars shown by Fig. 3 there 45 is a cut-out portion c at the thinner part, and, as shown in Fig. 5, such cut-out portion may also be formed at the thicker part of the collar, as at d, said cut-out portions being adapted to receive packing. The inside calibers or diameters of all are the same throughout and

the same as the caliber of the union A. The 50 thicker ends b of these collars are about the same thickness as the ends of union A, and the collars gradually diminish to a line in thickness at the other end. These collars are full and flat at their thicker end b and are to 55 abut against the flat ends of the union A, with packing-ring g intervening. Their calibers can be considerably enlarged or diminished by their expanding or contracting upon themselves, and thereby adapting themselves to 60 the size of the tubes E E, and still continually retain the full and flat face at their thicker ends.

The clamping-rings D D are screw-threaded on the inside for about three-fifths their 65 length to fit and screw on over the screw-threaded ends of union A. From this three-fifths point the caliber gradually diminishes to the other end f to the same caliber as that of union A, thus giving strength to this end 70 and forming a converging caliber a little smaller, but to correspond with and fit the outside of the wedge-shaped collars and to be drawn on over them. The outside of this end is octagonal for the wrench. 75

To apply the coupling, first slip on a clamping-ring over the end of each pipe E E, next slip collar B on one and collar C on the other pipe with their thin ends to the clamping-rings, then a packing-ring g on each tube. 80 Now slip on union A over the end of one tube, bringing the tube ends in line together and adjust the coupling so that the tube ends meet at about the center of inside of union A. Now bring the packing-rings and collars 85 against ends of union A and screw each clamping-ring on over the union in opposite directions. This will press the thick and smooth ends of the collars firmly against the ends of the union A, the packing intervening, and 90 will also squeeze the collars tightly around the tubes E E, so as to hold them very firmly and make a tight joint.

What I do claim as my invention, and desire to secure by Letters Patent, is— 95

1. In a pipe-coupling of the class described, the combination of the end abutting pipes, a tubular sleeve or union fitted over the abut-

ting ends of the pipes, clamping-rings fitted on the pipes at each end of said sleeve or union and having a tapering interior surface at one end, means for adjustably connecting the clamping-rings with the sleeve or union, and a collar formed as a spiral wedge fitted between the ends of the sleeve or union and the tapering interior surface of the clamping-rings, whereby adjustment of the clamping-rings upon the sleeve or union tightens the spiral wedges against the ends of the sleeve or union and about the pipes.

2. In a pipe-coupling of the class described, the combination of the end abutting pipes, a tubular sleeve or union fitted over the abutting ends of the pipes, clamping-rings fitted on the pipes at each end of said sleeve or union and having a tapering interior surface at one end, a screw-thread connection between the sleeve or union and the clamping-rings, and a collar formed as a spiral wedge of metal fitted between the ends of the sleeve or union and tapering interior surface of the clamping-rings, adjustment of the clamping-rings on

the sleeve or union, forcing the spiral wedge 25 against the ends of the sleeve or union and upon the pipes.

3. In a pipe-coupling of the class described, the combination of the end abutting pipes, a tubular sleeve or union fitted over the abutting ends of the pipes and having an exterior screw-thread, clamping-rings fitted on the pipes at each end of said sleeve or union and having interior screw-threads at one end and a tapering interior surface at the other end, a collar formed as a spiral wedge fitted between the ends of the sleeve or union and the tapering interior surface of the clamping-rings, and a packing interposed between the ends of the sleeve or union and the ends of the spiral wedge collars.

In testimony whereof I have signed my name to this specification in the presence of two subscribing witnesses.

JOHN YOUNG.
